UNITED STATES PATENT OFFICE.

WILFRED H. KUHN, OF DETROIT, MICHIGAN, ASSIGNEE TO WRIGHT-AUSTIN COMPANY, OF DETROIT, MICHIGAN, A CORPORATION OF MICHIGAN.

WATER-COLUMN ALARM.

Application filed July 6, 1925. Serial No. 41,527.

This invention relates to a safety device of the water column type for indicating the water level in a boiler by sounding an alarm when the water in the boiler reaches a predetermined high or low level.

It is of vital importance in devices of this character that the alarm controlled valve operate with accuracy and certainty, that is, that the valve be tightly closed at all times except when the sounding of the alarm is desirable and that it be quickly opened with certainty upon the water level reaching the danger point. It is an object of the present invention to provide an arrangement whereby the valve will operate with a maximum of certainty and whereby the liability of fouling is minimized and the valve and its seat may be very quickly and conveniently removed for inspection or repair.

A further object is to provide an arrangement whereby the life of the valve and its seat is doubled and whereby they may be quickly removed at any time for the purpose of cleaning or inspection without the necessity for demounting the water column or taking the same apart.

A further object is to provide certain other new and useful features in the construction and arrangement of an alarm control valve for water columns, all as hereinafter more fully set forth. With the above and other ends in view the invention consists in the matters hereinafter set forth and more particularly pointed out in the appended claims reference being had to the accompanying drawing, in which

Figure 1 is a vertical longitudinal section through a water column illustrating the application thereto of the present invention; and

Fig. 2 is an enlarged vertical section through a valve casing showing the construction and arrangement of valve embodying the present invention;

In the drawing a water column 1 of an old and well known form and construction is shown, said water column being adapted to be connected to a steam boiler in the usual manner, the cap or head of the column being provided with a steam inlet 3 and a water outlet 4 near its lower end. A second steam connection or opening 5 may be provided in the side of the column if found desirable and suitable openings 6 are provided in the front side of the column for

connecting thereto the usual water gauge, not shown.

The cap 2 is also provided with a screw-threaded opening into which is inserted a plug 7, said plug carrying the operating mechanism for the steam outlet valve which controls the sounding of the alarm, said control mechanism being of an old and well known type and comprising a bottom lever 8, which is pivotally attached to a bracket 60 carried by a rod 10 which is secured to the plug 7 at its upper end to depend into the water column and this mechanism also includes an upper lever 11 pivotally attached to a lug on the plug 7 and carrying a contact member 12 to be engaged by the float 13 when a high level of water in the boiler is reached and the water level in the column correspondingly rises. Upon fall of the water to a low level in the boiler, the water level in the column also falls until the ball 13 engages the lever 8. The lower end of a valve stem 14 is pivotally attached to the upper lever 11 in such a manner that upon contact of the float 13 with either the lever 70 8 or the member 12, the stem will be lowered and the valve 15 opened thereby, permitting steam from the upper end of the water column to pass out and sound an alarm which is preferably in the form of a whistle 16.

In order that the valve 15 may be readily accessible, it is located within the chamber 16 in a connection 17, the lower end of which connection is provided with a screwthreaded nipple 18 to screw into a recess or chamber 90 in the upper end of the plug 7. As this plug 7 extends completely through the wall of the cup 2 of the water column, this fitting or connection 17 is therefore located outside of the cup where it is always accessible and is preferably formed hexagonal in cross section so that a wrench may be applied thereto for disconnecting it from the plug 7.

In order that the valve seat 19 may also be readily accessible and detachable, this valve seat is made in the form of a disk which is seated within a recess 20 or seat in the end of a screwthreaded nipple portion 21 on the upper end of the connection 17 and to hold this valve seat in place, a fitting 22 is provided which has a chambered lower end internally screwthreaded to receive the nipple 21 and is also formed with an upwardly extending nipple 23 which is screwthreaded to engage within the hollow 100 105 110

stem 24 of the whistle 16. The valve 15 is therefore made readily accessible by simply unscrewing the connection 17 and the seat for this valve is also made accessible by 5 its location within the fitting 22 which may be readily unscrewed and the valve seat removed when desired.

In order that the valve 15 may have a long life and may be readily replaced when worn,

- 10 it is preferably made in the form of a short cylindrical body which is tapered at both ends to form valves, said valve being thus double ended so that when one of its tapered ends becomes worn, the valve may be removed from the valve stem 14 by knocking out the pin 25 and changing the valve, end for end. The lower end of the valve 15 fits within a chamber 26 provided therefor in the upper end of the valve stem 14 so that 20 said valve is carried by and made a detachable part of the valve stem.

The valve seat which is in the form of the disk 19 has an axial opening which is engaged by the upper tapered end of the valve 25 and thus the valve seats upwardly so that fouling of the valve seat is minimized. Further as the valve seat is in the form of a disk whenever the portion against which the valve seats becomes worn, this disk may be 30 removed and reversed so that the valve will engage within the other end of the opening through the disk and a new contact will be provided for the valve.

As the valve 15 is in the form of a short 35 cylindrical body provided with tapered ends, it may be readily hardened to prevent wear and by reason of being alike at both ends or having a seat end portion at each end, its life is doubled as when one end becomes 40 worn the valve may be reversed.

As previously stated, the vital part of an alarm device of this character, is the valve which controls the outlet of steam to the whistle. Should this valve become fouled 45 for any reason or should stick so that it did not immediately open upon the water in the boiler reaching the danger level, the device would be entirely useless and the purpose of the present arrangement of valve is to insure such positive and accurate operation. To further insure positive operation, it is very desirable that the valve be so arranged 50 that it may be conveniently inspected from time to time and in the present arrangement this may be quickly and easily accomplished as the members which form the casing for 55 the valve and its seat are located entirely

outside of the water column where they may be quickly unscrewed and the valve and its seat exposed to view.

Obviously, changes may be made in the construction and arrangement of parts within the scope of the appended claims without departing from the present invention and I do not therefore limit myself to the specific 65 construction shown.

Having thus fully described my invention what I claim is:—

1. The combination with a water column and a valve mechanism in said column comprising a depending rod having a bracket at its lower end, a bottom lever pivotally connected to said bracket, a top lever operatively connected to the bottom lever and a float operative between said levers, said column having an enlarged screw-threaded opening in its upper end; of a screw-threaded plug in said enlarged opening and formed with an axial bore and a lug extending downwardly into the column and to 80 which lug said top lever is pivotally attached and to which plug said depending rod is secured at its upper end, a valve, a valve stem for said valve and pivotally connected at its lower end to said top lever and extending upward through the bore of the plug, a valve casing carried by the outer end of the plug and formed with an axial bore of greater diameter than the diameter of said valve and valve stem, whereby the removal 90 of said casing from said plug will expose the valve and upper end of its stem above said plug, a fitting on the outer end of the casing, a detachable valve seat interposed between said fitting and the end of said casing, and an alarm member carried by said fitting.

2. A device for the purpose described and as characterized in claim 1 and further characterized in that said plug is screwed into 100 the enlarged opening in the column from the interior of the column outwardly, extending completely through the wall of the column and is provided with an end portion to engage the inner surface of said wall, and further characterized in that said valve casing is exteriorly angular in cross section and has a screw-threaded nipple at each end, one to engage within an enlargement of the bore of the plug and the other to engage 105 within said fitting.

In testimony whereof I affix my signature.

WILFRED H. KUHN.
